UNITED STATES PATENT OFFICE.

ADAM ALBERT McDONALD, OF BRUNSWICK, MARYLAND, ASSIGNOR OF ONE-HALF TO WALPER GRANVILLE MUSGROVE, OF SAME PLACE.

PRESSURE-EQUALIZER AND VACUUM-REGULATING VALVE.

SPECIFICATION forming part of Letters Patent No. 674,010, dated May 14, 1901.

Application filed January 22, 1901. Serial No. 44,451. (No model.)

To all whom it may concern:

Be it known that I, ADAM ALBERT McDONALD, a citizen of the United States, residing at Brunswick, in the county of Frederick and State of Maryland, have invented certain new and useful Improvements in Pressure-Equalizers and Vacuum-Regulating Valves; and I do hereby declare the following to be a full, clear, and exact description of the invention, such as will enable others skilled in the art to which it appertains to make and use the same.

My invention has relation to pressure-equalizers adapted to be applied to steam-cylinders or steam-chests; and it consists in the novel arrangement and construction of its parts, as hereinafter described.

The object of my invention is to provide a simple and effective attachment adapted especially to be applied to a locomotive-cylinder or steam-chest, the equalizer being so constructed and attached as to equalize the pressure on both sides of the piston-heads while the steam is cut off and the engine is moving and the pistons are reciprocating, thus effecting a great saving in wear and tear on the mechanism and packings and by equalizing the pressures permitting the piston to move freely, thus not interfering with the speed of the locomotive.

In the accompanying drawings, Figure 1 is a side elevation of a high and low pressure locomotive-cylinder with the equalizer attached thereto. Fig. 2 is a transverse sectional view of the equalizer cut on one diameter, and Fig. 3 is a transverse sectional view of the equalizer cut on a diameter at right angles to that upon which Fig. 2 is cut.

The equalizer consists of a cylindrical casing 1, having dependent from its bottom a pocket 2 and extending from its top a dome 3, the dome and the pocket extending horizontally at a right angle to each other. The equalizer is mounted on the cylinders 4 4. The bottom of a casing 1 is connected by means of the pipes 5 5 with the steam-chest. The dome 3 is connected by means of the pipes 6 6' to one of the cylinders and by means of the pipes 7 7' to the opposite end of said cylinders, the pipes 6' and 7' entering the large cylinder on top about five inches from

the heads of said cylinder to equalize the pressure on the large piston with the small one. A sliding block 8 is located in the casing, said block having located at its lower end and extending diametrically across the same a shank 9, said shank entering the pocket 2, said block having at its upper end an extension 10 entering the dome 3, said extension having an opening 11, adapted to come opposite the upper ends of the pipes 6 6' and 7 7' when the block 8 is in its lowest position in the casing.

If necessary, when using the engine simple a reducing-valve 12 of ordinary construction could be placed in the connection 13 to prevent too high pressure in the low cylinder.

In operation the device works as follows: When the steam is turned into the cylinders 4 4, the pressure thereby exerted through the pipes 5 5 elevates the block 8, thus causing the solid portion of the extension 10 to be interposed between the ends of the pipes 6 6' and 7 7'. When it is the desire to let the locomotive drift, the steam is cut off from the cylinders, and at the same time pressure being withdrawn from the under side of the block 8 the said block falls into the position as shown in Figs. 2 and 3, thus causing the opening 11 of the extension 10 to register with the pipe ends 6 6' and 7 7'. Thus as the piston-heads reciprocate the steam and air in the cylinders will pass rapidly back and forth through the pipes 6 6' and 7 7', and the piston-heads will at no time be operating against a steam or air cushion in the cylinders. It will thus be seen that the device is automatic in its action and will effect a great saving in wear and tear on the part of the cylinders and pistons.

Having described my invention, what I claim as new, and desire to secure by Letters Patent, is—

1. A device for equalizing the pressure on opposite sides of a piston within a cylinder, consisting of a receptacle having a removable block, connections connecting said receptacle with both ends of the cylinder said block having an opening and a means adapted to cause said opening to register with the cylinder connections when the steam is off, and a means

adapted to cause a solid portion of said block to be interposed between the cylinder connections when the steam is on.

2. In combination with a cylinder having a movable piston, a pressure-equalizer having connections connecting it with both ends of the cylinder, a sliding block having a solid portion adapted to be interposed between the ends of the said connection when the pressure is on in the cylinder, said solid portion adapted to be withdrawn from interposition between the connections when the pressure is off.

3. In combination with a cylinder having a moving piston, a pressure-equalizer consisting of a casing containing a sliding block, said block having an extension, said casing

having a dome adapted to receive said extension, connections connecting said dome with both ends of the cylinders, a steam connection entering said casing, the parts being so arranged that when the steam is on in the cylinder the pressure causes the block to move and interposes the solid portion of the extension between the ends of the cylinder-head connections, and when the steam is off removing said solid portion from interposition between the cylinder-head connections. 20 25

In testimony whereof I affix my signature in presence of two witnesses.

ADAM ALBERT McDONALD.
